TRANSPARENCY MOUNT

James C. Reddig and Kenneth A. Van Dyck,
Rochester, N. Y., assignors to Eastman Kodak
Company, Rochester, N. Y., a corporation of
New Jersey

Application July 8, 1950, Serial No. 11,028

Term of patent 14 years

(Cl. D61—1)

To all whom it may concern:

Be it known that we, James C. Reddig and Kenneth A. Van Dyck, citizens of the United States, residing in Rochester, in the county of Monroe and State of New York, have invented a new, original, and ornamental Design for a Transparency Mount, of which the following is a specification, reference being had to the drawings, forming a part thereof, in which:

Fig. 1 is a front elevational view of a transparency mount, showing our new design;

Fig. 2 is a rear elevational view of the transparency mount shown in Fig. 1;

Fig. 3 is a perspective view of the front of the transparency mount shown in the preceding figures; and

Fig. 4 is a sectional view taken on line 4—4 of Fig. 1 to illustrate the embossings in this mount.

We claim:

The ornamental design for a transparency mount, as shown.

JAMES C. REDDIG.
KENNETH A. VAN DYCK.
